CLAIM

The ornamental design for a mounting adapter for an automotive harness connector, as shown and described.

DESCRIPTION

FIG. 1 is a top, rear, right side perspective view of a mounting adapter for an automotive harness connector;

FIG. 2 is a bottom, front, left side perspective view thereof;

FIG. 3 is a right side elevation view thereof;

FIG. 4 is a rear elevation view thereof;

FIG. 5 is a left side elevation view thereof;

FIG. 6 is a front elevation view thereof;

FIG. 7 is a top plan view thereof; and

FIG. 8 is a bottom plan view thereof; and,

FIG. 9 is a top, front, left side perspective view thereof

shown with an automotive harness connector.

The broken lines are for environmental purposes only and form no part of the claimed design.
